UNITED STATES PATENT OFFICE.

JAMES ENGLISH AND WILLIAM L. ENGLISH, OF CHATEAUGAY, NEW YORK.

PACKAGE-TIE.

1,331,699.

Specification of Letters Patent. Patented Feb. 24, 1920.

Application filed September 25, 1919. Serial No. 326,154.

To all whom it may concern:

Be it known that we, JAMES ENGLISH and WILLIAM L. ENGLISH, citizens of the United States, and residents of the village of Chateaugay, in the county of Franklin, State of New York, have invented certain new and useful Improvements in Package-Ties, and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention relates to package ties and it has particular reference to such ties as may be employed in carrying mail packages and the like of various sizes.

An object of our invention is to provide a package tie that is simple and durable in construction and which comprises a suitable binding cord, such as a flexible link chain, of considerable length that permits the package tie to be employed for various sizes of packages. Our package tie also provides means for securely holding the elements of the package in close or pressed contact with each other, which is effected by means of a resilient leaf-spring member that, at all times, holds the flexible link chain member tautly about the package.

Another object of our invention is to provide a package tie which is adapted for carrying small packages as well as relatively large packages. The flexible link chain member, comprising the tying or binding cord of our package tie, serves as a ready and convenient means for securing the package tie about the package or bundle of mail that it is desired to carry.

While the annexed drawings and specifications describe one form of our package tie in detail, it is to be understood that the mechanical proportions of the elements comprising the package tie may be varied and that other modifications may be made therein without departing from the spirit and scope of the claims forming a part of this application.

Referring particularly to the drawings, Figure 1 is a side view in elevation of a portion of our package tie; Fig. 2 is an end view of the device shown in Fig. 1; Fig. 3 is a top plan view showing in detail the means for permanently attaching the link chain or

cord to one end of the resilient spring member and also means for adjustably securing, at will, the other end of the link chain member forming a part of our package tie; Figs. 60 4 and 5 show side and end views respectively, of our package tie applied to a relatively large bundle or package which, in this instance, is illustrated as being composed of mailing envelops.

Referring to the drawing, a resilient spring member 1, preferably composed of spring steel or similar material, is secured intermediate its ends between a thin wedge 2 and a relatively thick wedge 3 by means of a rivet 10. It will be noted that the exposed outer face of the wedge 2 is substantially flat, while the exposed outer face of the wedge 3 is preferably concave. By this means, our package tie may conveniently be adapted for carrying small packages when the wedge 3 is in contact with the package to be carried and for carrying relatively large packages when the wedge 2 is in contact with the package to be carried. When the thick wedge 3 is in contact with the package to be carried, the resilient spring member 1 is permitted to be bent to such degree as to press tightly against the lower edges of the package, in which instance a link chain member 6 may be tightly drawn around the package holding the elements thereof in close contact so as to preclude their being disarranged when being carried.

The link chain member 6 is permanently secured to the end 5 of the spring member 1 by any suitable means, such as is illustrated in Fig. 3. In the form shown the end 5 of the spring 1 is enveloped by a two-ply metallic piece that is bolted to the spring member 1 by means of a bolt 8. The other end of the spring member 1 provides a slot extending between tongues 4 which are formed and reinforced by means of a three-ply metallic piece that is bolted to the spring member 1 by the bolt 7.

In applying the package tie to a relatively large sized package, as shown in Figs. 4 and 5, the wedge 2 is brought into engagement with the package and the metallic spring 1 is concaved by proper manipulation so as to draw the chain member 6 tightly around the package. The links comprising the chain member 6 serve as locking or securing means for tautly holding the tie about the package after the chain has been properly received in the slot extending between the tongues 4.

In the form shown in the drawings, the link chain member 6 is of a common type in which each link comprises a relatively thin flat portion and an eyelet portion, that is relatively thick. The thin flat portions of the links are permitted to slide freely within the slot interposed between the tongues 4, while the eyelet portions of the links preclude the drawing of the chain through the said slot. In this manner the free end of the link chain is held securely to the spring member 1 after it has been tightly drawn about the package and received within the slot.

When it is desired to carry a relatively small package, the wedge 3, as explained above, is brought into pressed contact with the package in the place of the wedge 2. In this instance, the spring member 1 is permitted to be bent to a larger degree, thereby securely holding the elements of the smaller package in close contact with one another after the proper link of the chain member 6 has been engaged by the slot disposed between the tongues 4.

It will be understood that other forms of chain may be used than that shown in the drawings and that other securing means for engaging the free end of the chain with the spring member 1 may be employed, without departing from the spirit and scope of the following claims.

We claim as our invention:—

1. A package tie comprising a flat spring member slotted at one end, a flexible binder one end thereof being permanently attached to one end of said spring member and the other end thereof being adapted to engage, at will, the said slot formed in the spring member, and two wedge members secured to said spring member intermediate its ends, one of said members having a flat exposed

surface and the other a curved exposed surface.

2. A package tie comprising a flat spring member slotted at one end, a flexible binder one end thereof being permanently attached to one end of said spring member and the other end thereof being adapted to engage, at will, the said slot formed in the spring member, and two wedge members secured to said spring member intermediate its ends and severally disposed on opposite sides thereof.

3. A package tie comprising a flat spring member slotted at one end, a flexible binder one end thereof being permanently attached to one end of said spring member and the other end thereof being adapted to engage, at will, the said slot formed in the spring member, and two wedge members severally disposed on opposite sides of said spring member intermediate its ends, one of said wedge members being relatively thick and having its outer surface convexly curved and the other wedge member being relatively thin and having a flat outer surface.

4. A package tie comprising a leaf spring slotted at one end, a flexible metallic chain comprising link members, one end of said chain being permanently attached to one end of said spring member adapted to engage, at will, the slot formed in said spring member, and two wedge members of different thicknesses severally secured to said spring member intermediate its ends, one of said wedge members having a flat outer surface and the other of said wedge members having a convexly curved outer surface.

In testimony that we claim the foregoing as our invention, we have signed our names.

JAMES ENGLISH.
WILLIAM L. ENGLISH.
